UNITED STATES PATENT OFFICE.

EZRA S. PACKARD, OF HAMMONTON, NEW JERSEY.

BROODER.

SPECIFICATION forming part of Letters Patent No. 351,883, dated November 2, 1886.

Application filed September 2, 1886. Serial No. 212,513. (No model.)

To all whom it may concern:

Be it known that I, EZRA S. PACKARD, a citizen of the United States, residing at Hammonton, in the county of Atlantic and State 5 of New Jersey, have invented certain new and useful Improvements in Brooders; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

15 This invention relates to brooders for raising chickens in large numbers without the aid of the mother hen.

The improvement consists in the novel features presently to be described and claimed, and 20 shown in the annexed drawings, in which—

Figure 1 is a side view of a brooder embodying my improvements, parts being broken away. Fig. 2 is a section of the same on the line xx of Fig. 1. Fig. 3 is a detail view showing the means for closing the air-inlets. Fig. 25 4 is a plan view of one of the elevated platforms, and Fig. 5 is a perspective view of the artificial mother.

A represents the floor of the brooder, beneath which a series of compartments, B, are formed, which are separated by partitions b. Directly above these compartments are formed brooders C, each of which consists of an elevated platform, D, having sides d, to which 35 the wire-netting d' is secured. An air-chamber is formed between the floor and elevated platform, for the purpose of preventing the brooders from becoming overheated to the great detriment of the health of the chickens.

40 The height or distance of the platform from the floor can be regulated by set-screws D', located at each corner thereof and bearing upon the floor. Air is admitted to said space by inlets D'', formed in the side of pieces D', which 45 embrace the sides of the floor.

Tubes E, secured at their upper ends to the elevated platform, extend through openings in the floor, and afford communication between the compartments and the brooders. They 50 pass loosely through the floors, so as not to interfere with the raising and lowering of said platforms, for the purpose already set forth.

The artificial mother is placed directly over the protruding ends of the tubes E, and consists of a top, F, adjustably supported on pins 55

f, passed through each corner. The inner side of the top is cushioned in any desired manner, and curtains f', depending from the edges, serve to retain a sufficient amount of heat for the brooding of the chickens under said mother. 60

A series of heating-pipes, G, extends through the compartments for the purpose of warming the fresh air supplied thereto through the inlets or air-passages h. They run in any desired direction, either parallel or return-bends, 65 but preferably in the manner shown, in which G' extends the entire length of the brooder-house, and has branches G'' projecting therefrom at each end of the compartment, the outer ends of which are joined by a series of short 70 pipes, G'', united in a zigzag shape, as shown. Near each end the branches G'' are provided with valves g', for regulating circulation of the heating medium through said branches. The valves g'', arranged between the ends of the 75 branches G'', serve to cut off the heating medium from or direct it to any particular brooder.

In a compartment at one end of the series of brooders is located the heating apparatus, comprising the boiler H and tank I. At the 80 other end of the series connection is made with return-pipe J by a series of short pipes, j.

The inner ends of the air-passages h are closed by valves K, which are pivoted between their ends, one end of which is adapted to 85 close the opening, while the other end is bent at right angles, forming a handle, k, which extends upward through an opening in the floor, within easy reach for opening and closing said air-passages, as desired. 90

It will be noticed that the floor has a series of openings formed therein, corresponding to the position of the several valves g' g''.

Having thus described my invention, what I claim, and desire to secure by Letters Patent, 95 is—

The combination of a continuous series of brooders having compartments formed beneath them, the heating-pipes located in said compartments, the air-passages leading thereto, the valves for controlling the passages, the elevated platform, and means for raising and lowering it, substantially as and for the purpose described. 100

In testimony whereof I affix my signature in 105 presence of two witnesses.

EZRA S. PACKARD.
